BURNER

David P. Graham, Flushing, N. Y., and Robert C. Vroom, Montclair, N. J., assignors to Peabody Engineering Corporation, New York, N. Y., a corporation of New York

Application February 18, 1941, Serial No. 379,422

9 Claims. (Cl. 158—118)

This invention relates to fuel burners and more particularly to rotary fuel burners of the reaction type wherein fuel issuing from a reaction rotor drives the air fan.

The invention is particularly applicable to industrial gas or oil burners, although it may be applied to various burners which are adapted to use a fuel capable of furnishing the necessary reaction forces for driving the rotor.

An object of the invention is to provide a novel and improved burner of the above type in which the fuel is prevented from passing through the rotor bearings.

Another object is to provide a burner of the above type in which the bearings are cooled by the fuel supplied to the burner.

Another object is to provide a burner of the above type having novel and improved combinations of parts and details of construction.

Various other objects and advantages will become apparent as the nature of the invention is more fully disclosed.

Although the novel features which are believed to be characteristic of this invention are pointed out more particularly in the claims appended hereto, the invention itself may be better understood by referring to the following description, taken in connection with the accompanying drawings, in which a specific embodiment thereof has been set forth for purposes of illustration.

In the drawings,

Fig. 1 is a longitudinal section, taken along the line 1—1 of Fig. 2 illustrating the construction of a burner embodying the present invention;

Fig. 2 is a section taken on the line 2—2 of Fig. 1;

Fig. 3 is a longitudinal section taken on the line 3—3 of Fig. 4, illustrating a further embodiment of the burner;

Fig. 4 is a transverse section taken on the line 4—4 of Fig. 3;

Fig. 5 is a longitudinal section taken on the line 5—5 of Fig. 6 illustrating a still further embodiment of the invention and

Fig. 6 is a transverse section taken on the line 6—6 of Fig. 5.

Referring to the drawings more in detail, the invention is shown as applied to a burner for use in the burner opening 10 of a furnace wall 11. The burner comprises a cylindrical shell 12 adapted to seat within the opening 10 and defining an air passage 17 through which air for combustion is supplied. The shell 12 may be provided with a flange 13 secured against the outer

surface of the wall 11 for holding the shell in position. A spider 14 having a hollow hub 15 is mounted within the shell 12. The spider 14 may be adjusted longitudinally within the shell and 5 may be held in place by set screws 16.

The hollow hub 15 is provided with an inner wall 20 forming a central bearing chamber 21 and an outer wall 22 spaced from the wall 20 to form an annular fuel passage 23 which surrounds the bearing chamber 21. A housing 24

is joined to the hub 15 by spaced ribs 25 and constitutes a forward extension of said hub. The housing 24 comprises forward and rear walls 26 and 27 respectively forming an annular fuel chamber 28 which is in communication with the passage 23 through passages 29 in the ribs 25. In the embodiment shown, two ribs 25 are provided. It is to be understood, however, that three or more such ribs may be provided if desired.

20 The housing 24, ribs 25 and hub 15 are shown as formed in a single casting but they may be made as separate elements if desired. The space 30 between the housing 24 and the hub 15 is open to the atmosphere existing within the tube 12.

A shaft 31 is journaled for rotation in anti-friction bearings 32 and 33 in the bearing chamber 21 and projects at both ends from the hub 15, extending through the fuel outlet chamber 28. A fan 35 is keyed to the rear end of the shaft 31 by a key 36 and is held in position by a nut 37. A reaction rotor comprising a hollow cup 40 carrying hollow reaction arms 45 is keyed to the forward end of the shaft 31 by a key 41 and is secured by a nut 42.

30 The reaction arms 45 are provided with apertures 46 which are spaced along the arms so as to distribute fuel uniformly across the entire cross-sectional area of the burner opening. The 40 apertures 46 are positioned to produce rotation of the shaft 31 and associated apparatus by the reaction of the fuel issuing therefrom. A fluid seal is effected between the walls 26 and 27 of the housing 24 and the shaft 31 and the cup 40 45 respectively by suitable means shown as labyrinth packings 47 and 48.

A rotating deflector 50 is secured on a shaft 31 in the space 38 for directing radially any fuel which may pass the labyrinth packing 48 so as 30 to prevent building up eddy currents which might result in combustion of leakage gas in the space 30. Rotating oil flingers 51 and 52 are mounted on the shaft 31 on the outside of the bearings 32 and 33.

35 In the embodiment shown, the flinger 52 is

seated against a shoulder 53 on the shaft 31 and bears against the inner ball race 33a of the bearing 33. A spacer 54 extends between the inner ball race 33a of the bearing 33 and the inner ball race 32a of the bearing 32. The flinger 51 engages the inner ball race 32a, and a spacer 55 separates flinger 51 from the hub of the fan 35. The nut 37 accordingly serves to clamp the above mentioned elements in axial position on the shaft 31. Inasmuch as the fan 35 is keyed to the shaft 31, the shaft may be held against rotation thereby while the nut 37 is being tightened or loosened.

The deflector 50 is shown as seated against a shoulder 60 on the shaft 31 and a spacing member 61 extends from the deflector 50 to a central flange 62 of the cup 40, whereby the nut 42 clamps the reaction rotor and associated elements in position on said shaft. The keyed reaction rotor serves to hold the shaft 31 against rotation while the nut 42 is adjusted.

The forward (furnace) end of the bearing chamber 21 is substantially closed by a wall 63 of the hub 15. The rear end thereof may be closed by a plate 64, which may be secured to the hub 15 by suitable means, shown as screws 65. The outer ball race 33b of the bearing 33 may be positioned against a shoulder 66 in the wall 20. The outer ball race 32b may be held in position by a retaining ring 67, thereby securing the assembly against longitudinal movement.

Fuel may be supplied to the annular fuel passage 23 through a supply pipe 67 which may be threaded into a boss 68 in the hub 15. To permit assembly of the apparatus, the shell 12 may be provided with a slot 69 to receive the pipe 67. This slot may be closed by a cover 70 which may be positioned over the shell 12 after the burner has been assembled and may be secured by suitable means, shown as screws 71.

Operation

In the operation of this device, fluid fuel, such as gas or oil or atomized oil passes through the pipe 67 to the annular fuel passage 23, thence around the bearing chamber 21, through the passages 29 in the ribs 25 to the fuel supply chamber 28, thence through the hollow cup 40 to the reaction arms 45 whence it issues through the apertures 46. The reaction of the fuel issuing from these apertures serves to cause the arms 45 to rotate and thereby rotate the shaft 31 and the fan 35 attached thereto.

The fuel passing through the annular fuel passage 23 around the bearing chamber 21 serves to cool the same. The passage of air from the fan 35 over the hub 15 also assists in cooling the entire hub section. This air mixes with the fuel issuing from the apertures 46 of the reaction arms 45 to form a combustible mixture which is discharged into the furnace and burned.

Any fuel which leaks past the labyrinth packings 47 and 48 is picked up in the air stream to form a part of the combustible mixture. Inasmuch as the space 30 between the housing 24 and the bearing chamber 21 is maintained at the pressure of the passage 17 which is no higher than the pressure in the bearing chamber, there is no tendency for leakage fuel to enter the bearing chamber.

It is to be understood that suitable oil means, not shown, may be provided for lubricating the bearings in chamber 21. In certain instances, the bearings may be packed with grease, depending upon the construction thereof. In any event, the bearings are uncontaminated by the fuel and

the life of the apparatus is materially increased.

It is to be noted that by mounting the fan and reaction rotor at opposite ends of the shaft 31, the rotating parts may be more readily balanced, thereby increasing the stability of operation and eliminating the tendency to vibrate, features of importance in large, industrial installations. Furthermore, either the fan or the reaction rotor may be removed and replaced as desired for adjusting the burner for efficient operation with various types of fuel without dismantling the remainder of the apparatus.

Figs. 3 and 4

The embodiment of Figs. 3 and 4 is similar to that of Figs. 1 and 2, except that the reaction rotor is provided with a hollow shaft through which the fuel flows to the reaction arms. In this embodiment, parts similar to those of Figs. 1 and 2 have been given the same reference characters and the description thereof will not be repeated. A hollow shaft 75 is provided in place of the solid shaft 31 of Fig. 1. The fan 35 is shown as provided with a hub 76 which is threaded onto and closes the end of the shaft 75 and may be secured by a set screw 77. The reaction arms 45 are shown as attached to a hollow hub 78, which is also threaded onto the end of the shaft 75 and may be secured by a set screw 79. The hub 78 closes the forward end of the shaft 75 and forms a fuel passage to the arms 45. The rotating deflector 50 is adapted to slide over the shaft 75 and is held in place by suitable means shown as a set screw 80.

The inner ball race 33a is shown as held against a shoulder 81 on the shaft 75. The separator 54 extends between the inner ball races 32a and 33a and a spacer 82 extends from the inner ball race 32a to the hub 76 of the fan 35. The outer ball race 32b of the bearing 32 is held in position by a flange 83 formed on a cover 84 for the hub 15, which is secured by screws 85. The cover 84 is provided with a boss 86 which has a running fit with the spacer 82 to which it is sealed by a labyrinth packing 87. A similar labyrinth packing 88 is provided for the wall 63 forming the forward end of the bearing chamber 21.

The hub 15 is shown as provided with an extension 90 forming an inlet passage which is joined to a fuel supply pipe 91. The extension 90 passes through the slot 69 in the shell 12 in a manner similar to the fuel pipe 67 of Fig. 1.

The hollow shaft 75 is provided with a plurality of apertures 94 registering with the fuel supply chamber 28 and is adapted to supply fuel from the chamber 28 to the reaction arms 45.

The operation of this device is similar to that above described, the fuel passing from the supply pipe 91 through the annular fuel passage 23 around the bearing chamber 21, thence through the ribs 25 to the fuel supply chamber 28. From the fuel supply chamber 28, the fuel passes through the apertures 94 to the interior of the hollow shaft 75 and thence through the hub 78 to the arms 45 of the reaction rotor, whence it issues from the apertures 46 therein, causing the entire rotor to rotate as above mentioned.

The fuel flowing through the passage 23 and the air flowing over the hub 15 serve to cool the bearing chamber 21. Any fuel which leaks past the packings 47 and 48 is picked up by the stream of air for combustion. The bearing chamber 21 is sealed by the packings 87 and 88. Inasmuch as the space 30 is maintained at the pressure of

the passage 17, there is no tendency for leakage fuel to enter the bearing chamber or to flow therethrough. The bearings accordingly, as in Fig. 1, operate in an atmosphere of air and out of contact with the fuel.

Figs. 5 and 6

In the embodiment of Figs. 5 and 6, the burner is generally similar to that shown in Figs. 3 and 4, except that the fan and reaction rotor are mounted on the same end as the hollow shaft. In this embodiment, parts similar to those previously described have been given similar reference numerals and the description thereof will not be repeated. The fan 35 is shown as formed with a hollow hub 99 which is held against a shoulder 100 on the hollow shaft 75 by the hub 78 of the reaction rotor, which is threaded onto the end of the shaft 75, as described in connection with Fig. 3. The hubs 78 and 99 may be secured by set screws 101 and 102 respectively. The rear end of the shaft 75 is provided with a cap 104 which engages and secures the inner ball race 32a in position. A removable cover 105 is provided for closing the rear end of the bearing chamber 21. The cover 105 is shown as provided with a flange 106, which bears against the outer ball race 32b of the bearing 32 for holding the assembly in place. The cover may be secured by suitable means shown as bolts 107.

A cover 110 may be attached to the hub 15 by bolts 111. This cover 110 is spaced from the cover 105 to form a chamber 112 in communication with the annular fuel passage 23 and is provided with a boss 113 suited to receive a fuel supply pipe 114 which extends axially from the hub 15 to supply fuel to the chamber 112 at the closed end of the bearing chamber 21.

For controlling the flow of air through the shell 12, a shield 115 is provided which is adjustably mounted on the pipe 114 by means of a hub 116 and may be held by a set screw 117. The shield 115 is provided with a sight and ignition hole 118 having a cover 119 secured thereover as by a bolt 120.

In the operation of the embodiment shown in Figs. 5 and 6, fuel supplied from the pipe 114 passes through chamber 112, the annular fuel supply passage 23, the passages 29 in the ribs 25, the fuel supply chamber 28, the apertures 94, the hollow shaft 75 and the hollow hub 78 to the hollow arms 45. Flow of air for combustion is induced by the fan 35 above mentioned. The flow of air through the shell 12 is controlled by the shield 115, which may be adjusted longitudinally of the pipe 114 for this purpose.

When the burner is to be disassembled, the covers 105 and 110 are removed, thereby exposing the end of the shaft 75. The reaction arms 45 and the fan 35 are removed, the flinger 50 is released and the shaft pulled out rearwardly with the bearings 32 and 33.

In this embodiment the bearing chamber 21 is permanently sealed at one end, thereby preventing any passage of leakage fuel therethrough. Inasmuch as the fuel in the space 30 is at the pressure of the passage 17, there is no tendency for the fuel to pass into the bearing chamber 21.

In the embodiments shown, the fuel flowing through the annular passage 23 cools the bearing chamber. In certain instances, however, this passage may be omitted and the fuel may be supplied directly to the chamber 28. The fan and reaction rotor may be mounted at the same 75

end of the shaft in the embodiments of Figs. 1 and 3 or the construction of Fig. 5 may be used with a solid shaft as in Fig. 1 if desired.

It is to be noted that all of the above described 5 embodiments provide a fuel supply chamber which is separated from the bearing chamber by a space maintained at the pressure existing within the tube 12 so that all tendency for leakage fuel to flow into the bearing chamber and contaminate the bearings is eliminated, regardless of the pressure of the fuel in the supply chamber. The device is sturdy and dependable in construction, efficient in operation and well suited for commercial use.

15 Although certain embodiments of the invention have been shown for purposes of illustration, it is to be understood that the invention is not to be limited thereto but that various changes and modifications may be made therein as will be 20 readily apparent to a person skilled in the art. The invention is capable of various uses and is only to be limited in accordance with the scope of the following claims.

What is claimed is:

25 1. A fuel burner comprising a hollow stationary hub having a bearing chamber therein, an annular fuel supply chamber coaxial with said bearing chamber and spaced axially therefrom to provide an air space therebetween, a shaft journaled in said bearing chamber and extending through said fuel supply chamber, an air fan to supply air for combustion mounted on said shaft, a reaction rotor driven by the fuel for combustion mounted on said shaft to drive said shaft and said fan, said reaction rotor including a hollow hub member and reaction arms having passages communicating therewith and apertures forming reaction jets, and means to supply fuel from said annular fuel supply chamber to said reaction rotor, said air space preventing the building up of pressure in excess of that in the bearing chamber and thereby eliminating the tendency for leakage fuel to flow into said bearing chamber.

35 2. A fuel burner comprising a hollow stationary hub having a bearing chamber therein, an annular fuel supply chamber coaxial with said bearing chamber and spaced axially therefrom to provide an air space therebetween, a shaft journaled in said bearing chamber passing through said fuel supply chamber and extending forwardly beyond said fuel supply chamber and rearwardly beyond said bearing chamber, an air fan to supply air for combustion mounted 40 on the rearwardly projecting end of the shaft, and a reaction rotor driven by the fuel for combustion mounted on the forwardly projecting end of said shaft to drive said shaft and said fan, said reaction rotor including a hollow hub member and reaction arms having passages communicating therewith and apertures forming reaction jets, and means to supply fuel from said annular fuel supply chamber to said reaction rotor, said air space preventing the building up of pressure in excess of that in the bearing chamber and thereby eliminating the tendency for leakage fuel to flow into said bearing chamber.

45 3. A fuel burner comprising a hollow stationary hub having a bearing chamber therein, an annular fuel supply chamber coaxial with said bearing chamber and spaced axially therefrom to provide an air space therebetween, a shaft journaled in said bearing chamber and extending through said fuel supply chamber, an air fan to supply air for combustion mounted on said

shaft, a reaction rotor driven by the fuel for combustion mounted on said shaft to drive said shaft and said fan, said reaction rotor comprising hollow reaction arms and a hollow cup carrying said arms, said cup being mounted on said shaft and having its side spaced therefrom to provide a fuel passage to said hollow arms, said cup communicating with and effecting a fluid seal with said annular fuel supply chamber, whereby fuel is supplied from said chamber through said cup to said reaction arms, said air space preventing the building up of pressure in excess of that in the bearing chamber and thereby eliminating the tendency for leakage fuel to flow into said bearing chamber.

4. A fuel burner comprising a hollow stationary hub having a bearing chamber therein, an annular fuel supply chamber coaxial with said bearing chamber and spaced axially therefrom to provide an air space therebetween, a hollow shaft secured in said bearing chamber and extending through said fuel supply chamber and having a plurality of apertures formed therein in registration with said fuel supply chamber for receiving fuel therefrom, an air fan to supply air for combustion mounted on said shaft, a reaction rotor driven by the fuel for combustion mounted on said shaft to drive said shaft and said fan, said reaction rotor comprising hollow reaction arms and a hollow hub carrying said arms, said hub being mounted on said shaft to receive fuel therefrom and to supply the same to said hollow arms, said air space preventing the building up

of pressure in excess of that in the bearing chamber and thereby eliminating the tendency for leakage fuel to flow into said bearing chamber.

5. A burner according to claim 1 in which the bearing chamber is closed at one end to prevent passage of leakage fuel therethrough.

6. A burner according to claim 2, in which the bearing chamber is open to the atmosphere at both ends, whereby the pressure therein is equalized and passage of leakage fuel therethrough is prevented.

7. A burner according to claim 1 in which the fuel supply chamber is joined to said hub by a plurality of spaced ribs.

15 8. In a burner according to claim 1, a plurality of ribs joining said fuel supply chamber to said hub, said hub having an annular fuel passage therein surrounding said bearing chamber, channels in said ribs supplying fuel from said annular passage to said fuel supply chamber, and means supplying fuel to said annular passage at a point spaced from said ribs, whereby fuel for combustion is caused to flow around the bearing chamber for cooling purposes prior to passage to said fuel supply chamber.

20 9. In a burner according to claim 1, a rotating deflector mounted on said shaft in said air space between said hub and said fuel supply chamber, said deflector being adapted to prevent eddy currents of leakage fuel from building up in said space.

DAVID P. GRAHAM.
ROBERT C. VROOM.
